UNITED STATES PATENT OFFICE.

JOHN A. CARR, OF WALDEN, ASSIGNOR OF ONE-HALF TO SARAH M. DISNEY, OF BROOKLYN, NEW YORK; JULIA CARR ADMINISTRATRIX OF SAID JOHN A. CARR, DECEASED.

DOOR-HANGER.

SPECIFICATION forming part of Letters Patent No. 312,969, dated February 24, 1885.

Application filed August 28, 1884. (No model.)

To all whom it may concern:

Be it known that I, JOHN A. CARR, a citizen of the United States, residing at Walden, in the county of Orange and State of New York, have invented certain new and useful Improvements in Door-Hangers; and I do hereby declare the following to be a full, clear, and exact description of the invention, such as will enable others skilled in the art to which it appertains to make and use the same.

My invention relates to hangers for barn, warehouse, car, and other sliding doors or gates, and has for its objects the provision of a hanger with removable roller and renewable bearing, and of forms adapting it to be placed upon an old or new door by being set upon the outer surface thereof or placed in a mortise therein.

In carrying my invention into practice I provide a bracket to sustain one or both of the rails on which the rollers move, with an inclined top to receive and hold a shield or roof, which rests on and may extend out over the edge thereof to protect the ways or rails, hangers, rollers, and opening between the door and barn.

The rails are far enough apart to receive between them the neck of the hanger and permit the rollers on each side thereof to ride upon the rails.

The hangers are provided at the base or foot thereof with means for securing them to the door, which may consist either of an offset portion or a continuation of the neck, with a shoulder interposed, the former construction being adapted for use upon old doors, where it is desirable to secure the hanger upon the outer surface thereof, and the latter being adapted more especially for new doors, where a mortise can readily be made; but it will be understood that either form may be substituted for the other in an old or a new door. The neck portion of the hanger, which lies above the shoulder or offset, is provided with a bearing for the rollers. The construction of this bearing, by means of which the rollers are readily removable, is peculiar, and constitutes one of the distinguishing features of my invention. To produce it, I form a downwardly-extending cam-cut in

the neck or head of the hanger, and then join 50 the lower end of this cam-cut with a vertical cut closed at the top. The location of these cuts is such as to leave two overlapping points in the path of the roller-spindle as it is being set in place or removed, so that the roller cannot be jarred out of the hanger by any accidental motion which may be given to it, and yet is readily removable therefrom by the proper manipulation. The top of the vertical cut is provided with a removable seat 60 formed of some suitable journal-box metal—such as brass—so as to be renewable when worn through, and thus save the hanger.

As heretofore constructed removable hangers have been formed by bending a metallic 65 rod over the journal of the rollers, or a box set thereon; but this provides no means for securing the hanger against accidental removal from the roller as does the device herein set forth.

The accompanying drawings illustrate what I consider the best means for carrying my invention into practice.

Figure 1 is a perspective view of a building with my invention applied. Fig. 2 is an enlarged side elevation of a hanger showing roller in dotted lines. Fig. 3 is a central vertical section of the same, showing roller in full lines. Fig. 4 is a side elevation of another form of hanger; and Fig. 5 is a central vertical section 80 of the same, also showing sections of portion of barn, roof, bracket, ways, and roller.

Similar letters of reference indicate corresponding parts in all the views where they occur.

A is the side of the barn or other structure upon which the doors or gates B B are hung.

Along the side of the barn at suitable intervals are placed my brackets CC, which are formed with a sloping top, c', upon which the shield or roof piece D is supported. On the high side of the sloping portion or top c' a depending shoulder, c'', is formed, which affords means for securing the brackets to the building, and leaves the entire top of the bracket free to receive the shield, which is thereby permitted to lie up snugly against the edge or face of the barn.

E E' are the ways or rails upon which the rollers on the hangers ride. The outer one, E, is supported by the vertical limb c* of the brackets, which has a shoulder or inwardly-extending lug, as shown, upon which the rail E rests. The inner rail, E', is secured directly to the side of the barn or other structure, as shown; or it may be supported by the bracket by having the shoulder c* extended down far enough to receive it, in which case the entire way will be sustained upon the side of the barn through the medium of the brackets alone.

F F are the rollers which move upon the ways, and by which the hangers are supported. By preference these rollers are formed double, with their spindle between the two parts.

G G are the hangers, whose necks g g lie between the rails, and in which are provided the bearings for the roller-spindles. These bearings and the manner of securing the roller-spindles therein are such as to make the rollers readily removable without taking the hangers apart, and yet prevent the removal of the rollers by accidental jars or movements. To produce the bearings with these qualities, I form a downwardly-projecting curved slot or cam-cut, h, and to the lower end thereof join an upright or vertical slot, h', closed at the top.

In setting the roller in place the spindle is first let down into the curved slot h, and then up the vertical slot h', in the top of which is the seat for the spindle. It will be observed that in thus being placed two overlapping points, i j, are presented to the direct path of the spindle, and that the said spindle is compelled to be moved around and over these points before it can be properly seated, and in being removed the process is equally as complex, the movement being reversed; and it will also be observed that in removing the spindle the hanger must first be given an upward movement, and then a combined downward and lateral movement to effect the displacement of the rollers, a condition of affairs not likely to result from accidental causes.

At the closed top of the slot h', where the spindle of the rollers finds a seat, is provided a removable metal seat, k, formed of some suitable journal-box metal, as babbitt, brass, or alloy, which can readily be removed and renewed as it becomes worn. This seat k is secured in place by being made to fit snugly in a suitable opening formed at the top of the upright slot h', and not only affords a means for renewing the bearing of the spindle when

it becomes worn without having to renew the entire hanger, but insures smoothness of action, and reduces the friction and wear upon the spindle to its minimum, thereby saving both hanger and rollers. This construction of hanger is strong and reliable, as it is made essentially of one piece of material, and at the same time makes the removal and replacement of the rollers a matter of great ease and facility.

The lower end of the hanger, which is to be secured upon the door, may be formed in either of two ways, as already stated. As shown in Figs. 2 and 3, it is provided with an offset and an attaching-ear, G', set out of line with the neck of the hanger, adapted to be placed upon the outer surface of the door and bring the neck and rollers directly over the door centrally, so as to make it hang squarely thereon. This form of hanger is especially adapted for use upon an old door. The other form, (shown in Figs. 4 and 5,) in which a shoulder, g*, is employed to separate the neck portion from the attaching portion, is constructed in rectangular form, and extends in line with the neck, and is in effect merely an extension thereof with the interposed shoulder. This is marked by the letter G', and is adapted to be inserted in a mortise or suitable opening in the body of the door at the top, and on account of this is especially applicable to new doors; but either form can be used upon old or new doors with about equal advantage. They are held thereon or therein by screws or rivets, as shown.

The operation of sliding doors is so well understood that it is not necessary to repeat it here, and when my devices are applied the operation is about the same as the ordinary well-known devices.

Having thus described my invention, what I desire to claim, and secure by Letters Patent, is—

1. A hanger for doors having a slot curved downward and upward and terminating in a bearing for its rollers, substantially as set forth.
2. A door-hanger having an entrance-slot of substantially quadrant shape, the journal end of which is provided with a detachable bearing, as set forth.

In testimony whereof I affix my signature in presence of two witnesses.

JOHN A. CARR.
mark.
